CASS L. KENNICOTT, OF CHICAGO HEIGHTS, ILLINOIS, ASSIGNOR TO THE KENNICOTT COMPANY, OF CHICAGO HEIGHTS, ILLINOIS, A CORPORATION OF ILLINOIS.

CALCULATING-MACHINE.

1,169,724.

Specification of Letters Patent. Patented Jan. 25, 1916.

Application filed March 22, 1915. Serial No. 16,155.

To all whom it may concern:

Be it known that I, CASS L. KENNICOTT, a citizen of the United States, residing at Chicago Heights, in the county of Cook and State of Illinois, have invented a new and useful Improvement in Calculating-Machines, of which the following is a specification.

My invention relates to improvements in calculating machines.

The object of my invention is to provide a machine suitable for use in manufacturing establishments where a number of workmen are employed, for the purpose of calculating or integrating continuously the labor cost of various manufacturing processes. Thus where a number of employees are simultaneously engaged in the production of any specific manufactured product or class of products, it is advantageous to be able to tell at any moment the total labor cost which has up to that time been incurred in producing the specific product or class of products under consideration. By my invention this result is accomplished in a simple and accurate manner and by a wholly automatic machine.

Various other secondary advantageous results are at the same time rendered possible by the use of my machine, as will more fully appear from the following detailed description of one specific embodiment of the invention. In this description reference will be had to the accompanying drawings, in which—

Figure 1 is a side elevation of one form of machine embodying my invention; Fig. 2 is a rear elevation of the machine shown in Fig. 1; Fig. 3 is a front elevation; Fig. 4 is an enlarged perspective view of a workman's plug suitable for use in connection with my machine; Fig. 5 is a top plan view of the base-plate of my machine, showing the normal gearing of the same; and Fig. 6 is a view similar to Fig. 5, showing a different gear train in use.

Referring more particularly to the drawings, numeral 10 designates the base-plate or frame of my machine, and the numeral 11 designates the indicating board which as shown consists of a comparatively narrow upright plate having its front face 12 grad-

uated, as indicated at 13. On top of the indicator board is mounted as by the brackets 14 a curtain roll 15, upon which is wound 55 a strip or tape curtain 16, which may have a weighted end 17. An oscillating arm 18, which is preferably journaled concentrically with the curtain roll 15, carries a pawl 19 which travels over the surface of and engages a ratchet wheel 20 mounted on the roll 15. The arm 15 is operated by a vertical link 21, which extends downwardly behind the indicator board, and at its lower end is pivoted to a slide block 22, which 65 travels in a slot 23 formed lengthwise of a horizontal rocker arm 24, which is pivoted to the base plate 10, as shown at 25. A helical compression-spring 26, which is fastened at one end to the arm 24 and at the 70 other to the link 21, tends always to draw the latter toward the pivot 25 of the rocker arm. The rocker arm 24 is designed to be continuously operated as by a cam 27 upon a shaft 28, which is suitably journaled on 75 the base plate and extends within a gearbox 29 mounted on the latter. The gearbox 29 may contain a constant-speed driving motor 30, the motor-shaft of which is provided with a pinion 31, which drives a 80 counter-shaft 32, and through the latter drives the shaft 28 upon which the cam is secured.

In Fig. 5 I have shown the counter-shaft 32 as provided with one set of reducing 85 gears, which I will call the normal gearing, and in Fig. 6 I have shown the counter-shaft provided with a different set of gears, which I will call the overtime gears. It will be readily understood that accordingly as the 90 gear connections between the motor and the shaft 28 are altered the relative speeds of the two shafts may be varied. The provision of an intermediate counter-shaft such as I have illustrated is merely a convenient 95 method of effecting this speed variation of the shaft 28, considering the motor 30 as a constant-speed motor.

The operation of my machine as so far described is as follows: The motor 30 being 100 energized from some suitable power source and driven at a constant speed, through its gear train acts to drive the shaft 28 at a constant speed bearing a definite relation to

the motor speed, according to the gear ratios employed. Through the cam 27 the shaft 28 will operate to oscillate the rocker arm 24 at the predetermined speed rate, and 5 if the slider block 22, to which the link 21 is fastened, be moved to any position not coincident with the pivot 25 of the rocker arm, the link 21 will be reciprocated to oscillate the arm 18 and intermittently drive the roll 10 15 to lower the curtain 16 downward over the graduated face of the indicator board 12. In the drawing I have shown a small idle roller 15', which guides the curtain onto the front face of the board. In connection 15 with this description it will be noted that the amplitude of oscillation of the arm 18, and in consequence, the angular movement of the roll 15, at each oscillation will be dependent upon the position of the slider 20 block 22 within the slot 23, that is, if the slider block be near the pivoted end of the arm 24 the link 21 will have only an exceedingly small lift at each oscillation of the arm, while as the slider block is moved outwardly toward the free end of the arm, the movement of the link will proportionately increase. There are then two factors which 25 govern the speed at which the curtain 16 moves downwardly across the face of the indicator board, these factors being: 1, the speed of the shaft 28 which drives the cam, and, 2, the position of the slider block 22 with respect to the pivot 25.

In order to enable my machine as above 35 described to be used for calculating shop costs I prefer to make use of a number of plugs, which I call workmen's plugs and which may conveniently have the rectangular form shown in Fig. 4. Each plug will 40 preferably consist of a body portion 40 having a handle 41, and on the face of the plug, opposite the handle, I prefer to provide the plug with type members, designated 42. These type members are immaterial to the 45 operation of the plugs in connection with the machine which forms the subject matter of the present invention. They are provided, however, as a preferred construction, in order to permit of the operation of this 50 machine in combination with the recording clock mechanism, which forms the subject matter of my co-pending application, Serial Number 16156, filed Mar. 25, 1915, and for use in the system or method of keeping shop 55 costs by the use of these two machines.

Returning to the consideration of the specific machine which forms the subject matter of my present invention, each of the workmen who are employed on the particular "job," a cost record of which is to be kept by my machine, will be provided with one of the plugs 40. These plugs will be identical in every dimension except as to their width, that is, the distance between the faces 65 43 and 44. This distance or width of the

70 plug will be a function of the hourly wage or salary of the particular employee to whom the plug is assigned, as, for example, if a certain class of workmen are compensated at the rate of fifty cents per hour, each of these workmen might be provided with a plug having a thickness of one inch. A certain other class of workmen, whose hourly wage would be 25 cents, would then be provided with a plug having a width of one-half inch, and according to this scheme the wages or hourly labor cost for each workman would be proportionate to or a function of the width of the plug which is 75 assigned to him.

80 For the purpose of rendering clear a preferred manner of making use of my machine I will set forth briefly a common system of factory accounting.

85 When plans are made for the production of any particular product or class of manufactured products it is common to estimate as nearly as possible the cost of such product or class of products, dividing such cost into its proper proportions as to labor, material 90 and other factors. Since it is with labor costs only that I am concerned at the present time, we will assume that the estimated labor cost of a certain manufactured product is to be twenty dollars. Returning to the prior 95 illustration with relation to the workman's plug 40, it will be assumed that the standard wage scale is fifty cents per hour. The total labor cost of twenty dollars would, therefore, be equivalent to forty hours' labor of one man 100 at the standard wage scale. Referring now to the graduations 13 upon the indicator board 12, it will be seen that these graduations run from a zero mark intermediate the length of the board in both directions, upward and downward. For preparing my 105 machine for integrating and indicating costs of the production of this article chosen as an illustration, the roll 15 will be manually operated to bring the curtain 16 to the fortieth upper graduation on the scale 13 and at the same time the adjustable indicator 50, which may be clamped to the side of the board in any desired position, is set opposite the fortieth graduation. At this time 110 the motor 30 may or not be operated, it being immaterial so long as the slider 22 is swung near the pivot 25 as to fail to rock the arm 18 the distance of one ratchet tooth of the roll 15. As the workmen report for duty 115 and are assigned to the particular "job" which is being considered by way of example, each workman will deliver his plug to the superintendent or despatcher who has charge 120 of the machine. As each plug is received it will be inserted in the slot 23 of the arm 24 and between the slider block 22 and the pivot end of the arm. The parts are so designed and proportioned that when a single 125 standard width plug is inserted behind the 130

slider block 22 the mechanism will operate at such a speed as to lower the curtain across one of the graduations 13 in a period of one hour. If, therefore, a single workman, 5 whose wage was equal to the standard wage, were assigned to the "job" under consideration, his plug would be placed behind the slider block 22 and the machine would operate to continuously lower the curtain 16 at 10 the rate of one graduation per hour. If the workman were called away from this "job" to attend to other duties, or if the "job" extended over a period of several days, the plug would be removed and reinstated accordingly, and at any time up to the completion of the "job" the total number of hours which the workman had spent upon the "job" would be indicated visibly upon the face of the indicator board by the distance between the bottom of the curtain and 15 the manually set indicator 50. At the same time the distance of the curtain above the zero mark would be indicative of the time left to complete the "job" within the original estimate, and if the time required to complete the "job" exceeded the original estimate the curtain would travel beyond the zero mark and cover the graduations of the lower or negative scale, so that this overtime, or time in excess of the estimate, would 20 also be indicated. If the completion of the "job" required labor out of the usual hours and for which a wage higher or lower than the standard wage is paid—if, for instance, 25 it was necessary to work on a holiday to complete the "job" and holiday pay rates were double those of ordinary pay rates, then the gear train connecting the motor 30 and the shaft 28 might be changed to drive 40 the latter shaft at double speed during the period of this holiday employment, and the machine would act continuously to integrate the labor cost on the "job" according to this advanced wage scale.

45 In the above illustration of the method of using my machine I have assumed that a single workman was employed on the "job" under consideration. In fact, however, my machine finds its greatest usefulness where 50 the "job" is one requiring the services of a comparatively large number of employees belonging to different wage classes. The operation of the machine is exactly the same as outlined above in this instance. As each 55 new workman is assigned to the "job" his plug is placed with the other plugs back of the slider block 22, and the stroke of the link 21 becomes proportionately increased for each oscillation of the rocker arm. In 60 such large "jobs" as were last mentioned and in which my machine finds its greatest usefulness, it is frequently necessary that some or all of the workmen be temporarily shifted or assigned to emergency work. To 65 keep a complete record of labor costs under

such conditions according to the methods hitherto in use involves a considerable amount of clerical labor, while by the use of my machine such shifting of the workmen requires only the removal and rein- 70 statement of the plugs within the machine, which operation may be performed by the superintendent or despatcher who assigns the workmen to their tasks.

One of the primary advantages of my 75 machine lies in the fact that by the instantaneous reading of the indicator board the following facts may be ascertained with respect to any particular "job": 1, the estimated labor cost of the "job"; 2, the labor 80 cost incurred up to that minute on the particular "job"; 3, the number of workmen and the wages of each now employed on the particular "job"; 4, the approximate time 85 which will be required according to the original estimate to complete the "job."

In mounting my machine in a factory or workshop it may be conveniently arranged with the indicator board within the shop itself, so that it may be viewed by the workmen and may serve as a continuous reminder to them of the estimated cost of the "job" on which they are employed, and will also enable them to judge of whether they are making as rapid progress as will be required to come within the estimate. The gear box and rocker arm in which the plugs are mounted may be located inside the despatcher's or superintendent's office, so that there will be no unauthorized interference 95 with the operation of the machine.

In the foregoing illustration of a preferred method of making use of the machine I have taken for example that system of 100 factory accounting in which the unit of labor cost is a "standard hour." It will readily be understood that any other unit of labor cost might be used, that is, the cost might be expressed directly in dollars and cents and the board so graduated, the parts 105 then being so proportioned as to function properly, when employing this system of units. It will be understood, also, that various methods of graduating the indicator 110 board and various forms of movable indicators operable from the machine to travel upon the board might be used without departing from the spirit of my invention. I 115 wish it to be understood, therefore, that the foregoing description is illustrative only and for the purpose of making my invention more clear, and that I do not regard my invention as limited to the particular construction and arrangement of parts shown 120 and described, nor to any of them except in so far as such limitations have been included within the terms of the following claims, in which it is my intention to claim all novelty inherent in my invention in as broad a manner as is possible in view of the prior art. 125

What I claim and desire to secure by Letters Patent is:

1. In a calculating machine of the type described, a time-controlled driving-motor, an integrating indicator driven from the said motor, and a step-by-step speed adjusting means for the said indicator, each step of adjustment representing a time cost unit, whereby the total time cost is integrated.
2. In a machine for the purpose described a movable indicator, a continuously operated time controlled motor and driving connections between said motor and said indicator, the said connections including a plurality of removable elements arranged to govern the speed of movement of the said indicator, whereby movement of the indicator may be a function of the time and of the presence or absence of the said removable elements.
3. In a machine for the purpose described a movable indicator, a continuously operating time controlled motor, intermittently acting driving connections between said motor and said indicator, and a plurality of removable elements for varying the amplitude of motion of said intermittently acting means.
4. In a machine for the purpose described an indicator, a rocker arm, connections for continuously moving said indicator from the oscillatory movement of said rocker arm, time controlled means for oscillating said rocker arm, and a plurality of removable elements arranged to vary proportionately to their number the movement of said indicator at each oscillation of the rocker arm.
5. In a machine for the purpose described, an indicator, an oscillatory arm for moving the said indicator, time controlled means for oscillating the said arm, and a plurality of removable elements adapted to vary the amplitude of oscillation of the said arm.
6. In a machine for the purpose described an indicator board having graduations thereon, a movable indicator element adapted to travel over the graduated surface of the board, intermittently acting time controlled means for moving the said indicator, and a plurality of removable ele-
- ments arranged to vary the movement of the said indicator at each operation of the said driving means.
7. In a machine for the purpose described a time controlled driving motor, an oscillatory arm operable from the said motor, a plurality of removable elements for varying in a step-by-step relation the amplitude of oscillation of the said arm, a movable indicating element, and driving connections between said oscillating arm and said indicating element.
8. In a machine for the purpose described a time controlled driving motor, an oscillatory arm operable from the said motor, a slide block mounted to travel lengthwise of the said arm, a plurality of removable elements for fixing the position of the said slide block, a movable indicating element, and connections between said element and said slide block for driving the former from the latter.
9. In a machine for the purpose described a time controlled driving motor, an oscillatory arm operable from the said motor, a slide block adjustable lengthwise of the said arm, a plurality of removable plugs for fixing the position of the said slide block, an indicator board having graduations thereon, a movable indicating element adapted to travel across the graduated face of the board, and connections for driving the said indicating element from the said slide block.
10. In a machine for the purpose described, a time controlled driving motor, an oscillatory arm operable from the said motor, a slide block adjustable lengthwise of the said arm, a plurality of movable plugs mounted in said arm for fixing the position of the slide block therein, an indicating board having graduations on its face, an indicator element movable across the face of the said board, a ratchet and pawl mechanism for moving the said indicator element, and driving connections between said slide block and said ratchet and pawl mechanism.

CASS L. KENNICOTT.
